FOREIGN PATENT DOCUMENTS

DE 202017107139 U1 * 2/2019 ..... B23C 5/26

Primary Examiner — Brett Miller*Assistant Examiner* — Fitzgerald L Butac(74) *Attorney, Agent, or Firm* — Muncy, Geissler, Olds & Lowe, P.C.(57) **CLAIM**

The ornamental design for a cutter head, as shown and described.

DESCRIPTION

FIG. 1 is a perspective view of a cutter head showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.

The broken lines depict portions of the article that form no part of the claimed design.

1 Claim, 8 Drawing Sheets---
